UNITED STATES PATENT OFFICE.

WILLIAM R. LITZENBERG, OF PORTLAND, OREGON.

INCANDESCENT LAMP AND REFLECTOR.

1,075,924.

Specification of Letters Patent. Patented Oct. 14, 1913.

Application filed May 31, 1912. Serial No. 700,342.

To all whom it may concern:

Be it known that I, WILLIAM R. LITZENBERG, a citizen of the United States, residing in the city of Portland, county of Multnomah, and State of Oregon, have invented 5 certain new and useful Improvements in Incandescent Lamps and Reflectors, of which the following is a specification.

My invention relates to incandescent 10 lamps and reflectors and more particularly to certain improvements in the construction of an incandescent lamp, whereby a combination shade and reflector can be conveniently and detachably secured thereto and 15 carried thereby, without the use of supporting rods or chains from the ceiling, fixture, or chandelier, which rods, chains, or other supports, cast shadows, and also make difficult the insertion and removal of the lamps 20 into and from their sockets.

My idea is to provide an incandescent 25 electric lamp, for example, at its outer extremity, with attaching means whereby a combination shade and reflector can be quickly and conveniently attached directly 30 thereto and supported thereby for the purpose of shading or hiding the lamp, with its glare, from the eyes, and at the same time, reflecting the light therefrom against the 35 ceiling, or the wall, but better still, against an oppositely facing reflector of high light-reflecting efficiency, to be reflected or diffused as desired, depending upon the form 40 of reflector used. If the light be reflected directly against the bare wall or ceiling, much of it is absorbed and lost. On the 45 other hand, by placing the lamp between two opposed reflectors of proper coöperating forms, and of high light-reflecting efficiency, all of the light can be reflected and 50 directed, or diffused generally, depending upon the relative shapes of the opposing reflectors, while at the same time the lamp with its glare is shaded, or wholly hidden 55 from view. By constructing an incandescent lamp so that a reflector can be attached directly thereto, I avoid the use of hanging chains, rods and other supports for such indirect reflector, and I also avoid the shadows 60 which would be cast thereby. Such a lamp makes it possible, with the use of two proper reflectors, and the ordinary socket, to shade 65 the lamp and reflect all of the light to one location, or to diffuse it generally throughout the room, without the use of expensive chandeliers or other unnecessary supporting ap-

paratus. In other words, my invention provides a simple, practical and economical means for indirect lighting, which is applicable alike to the ceiling or side wall, with a 60 maximum efficiency.

The invention will be readily understood from the foregoing, and from the following description of two embodiments thereof, reference being had to the accompanying sheet 65 of drawings, illustrating the same, and in which,—

Figure 1 is a side elevation, partly in section, illustrating one form of the invention; Fig. 2 is a similar view showing a slightly 70 modified form thereof; and Fig. 3 is a fragmentary inside plan view of the indirect reflector of Fig. 2, showing its means of attachment to the lamp.

Referring now to the drawings, 1 designates my improved incandescent electric lamp, provided with the usual threaded socket 2, and provided at its opposite end with an attaching, or supporting means, for a combination shade and reflector, herein- 80 after referred to as an indirect reflector. This attaching means is shown as a reduced threaded portion 3, in Fig. 1, and as a head or knob-like portion 3' in Fig. 2. A shade 4 of high light-reflecting efficiency is provided, and may be supported at the socket end of the lamp in any of the well known ways, whereby to directly reflect the light as desired. An indirect shade and reflector 5 is provided and adapted to be attached to 90 the lamp 1. In Fig. 1, the indirect reflector 5 is provided with a threaded socket 6, adapted to be screwed upon the reduced threaded portion 3 of the lamp 1; while in Fig. 2, I have shown the indirect reflector 5 95 provided with a yoke-like member 7, adapted to fit upon the neck like portion of the lamp 1. It is to be understood, of course, that any means for directly attaching the indirect reflector to the lamp may be used, 100 the object being to make possible the attachment of an indirect reflector to an incandescent electric lamp, whereby to shade or hide the lamp, with its glare, from the eye, and at the same time produce an efficient indirect light. For example, my incandescent electric lamp is screwed into the ordinary socket in the ceiling, or side wall, and one of my indirect reflectors placed thereupon. The lamp itself is hidden from view while the 110 light therefrom is reflected indirectly against the ceiling or side wall, as in the in-

direct lighting devices now used, which are basket-like fixtures within which ordinary incandescent lamps are placed. It is objectionable, however, to reflect the light 5 against the wall, for the reason that so much of the light is absorbed thereby, and only a small percentage of its efficiency is secured. By placing a direct reflector of the proper form and of high light-reflecting efficiency 10 at the socket, which is easily done, all of the light from the lamp can be reflected as desired, or diffused generally out into the room, depending entirely upon the relative forms of the opposing reflectors.

15 While I have shown and described two simple forms of my invention, I am aware that changes can be made therein without departing from the spirit thereof and I do not, therefore, limit the invention to the particular forms shown for purposes of illustration, except as the same may be limited by 20 the hereto appended claims.

I claim:

1. An incandescent lamp globe having at its outer extremity and as an integral part 25 thereof a supporting element and a combination shade and indirect reflector supported thereby at a space therefrom.
2. In combination, an incandescent lamp having at its outer extremity a supporting 30 element made as a part thereof, and a combination shade and indirect reflector detachably supported thereby at a space therefrom.
3. An incandescent lamp having its extremity provided with a threaded portion, 35 and a reflector for indirect lighting detachably supported thereby.

Signed at Portland, Oregon, this 24th day of May, 1912.

WILLIAM R. LITZENBERG.

In the presence of—

DANIEL E. POWERS,
MARGARETE JASCHINER.
